LEAF PULVERIZING DEVICE

Helen V. Sturdivant and Minor R. Ross, Houston, Tex.

Application December 4, 1953, Serial No. 396,232

1 Claim. (Cl. 55—113)

This invention relates to new and useful improvements in a leaf disposal device.

It is an object of this invention to provide a leaf disposal device that will pick up leaves from the ground and pulverize them and then redeposit them on the ground for fertilizer.

It is another object of the invention to provide a sanitary means for disposing of fallen leaves that will eliminate the fire hazard present with the popular method of raking fallen leaves into a pile and burning same, and that will greatly reduce the labor of leaf disposal as it is presently accomplished.

With the above and other objects in view, this invention has relation to certain novel features of construction and operation more particularly described in the following specifications and illustrated in the accompanying drawings, wherein:

Figure 1 is a side elevational view, partly in cross section, taken on the line 1—1 of Figure 3.

Figure 2 is an end view taken on the line 2—2 of Figure 1.

Figure 3 is a side elevational view.

Figure 4 is a fragmentary cross sectional view taken on the line 4—4 of Figure 3, and

Figure 5 is an enlarged fragmentary view of the pulverizing grate employed.

Referring now more particularly to the drawings, the numeral 1 designates a framework on which suitable wheels, as 2, 2 are mounted, and which has a suitable housing, as 3, covering the framework, and a suitable means for imparting power, such as the engine 4, mounted on the housing 3. A drive pulley 6 on the engine 4 drives the driven pulley 7 on the framework 1 and the pulley 7 is secured to the shaft 8, which rotates with the pulley 7, and a driving pulley 9 is also secured to the shaft 8 and rotates therewith. A belt, as 10, connects the driving pulley 6 with the driven pulley 7, and a belt, or other driving means, 11, connects the pulley 9 with the pulley 12, and the pulley 12 is secured and rotates the shaft 13.

A drum 14 is mounted on the axle 15 inside of the housing 3 and is connected, preferably by welding, to the shaft 8, and is rotated thereby. Longitudinally mounted on the drum 14 are a series of outwardly extending brushes, 16, composed of wire, or the like. The axle 15 of the drum 14 is preferably square to provide a firm connection with the drum.

Inside of the housing 4 and extending downwardly and rearwardly from a point immediately to the rear of the brushes 16 is a table 17. A pulverizing drum 19 is mounted in the housing 3 adjacent the end of the table 17. The drum 19 has outwardly extending brushes 23 composed of wire, or the like, mounted in its periphery, and the table 17 is bent downwardly adjacent the end of the brushes 28 of the drum 19, and curved to conform

2

to the contour of the drum 19, forming a guard 20. Mounted on the opposite side of the drum 19, and preferably secured to the housing 3, is a grate 21, which is of the same longitudinal dimension as the drum 19, and which is formed to follow the contour of the drum 19 to a point beneath the drum and adjacent the terminus of the guard 20. The surface of the grate facing the drum is divided into alternate series of brushes 23 and perforations 22.

10 A suitable clutch, as 24, may be provided to bring the driving pulley 6 into driving relation with the driven pulley 9. A suitable propelling means, as the handle 25, may be provided and a clutch control 26 may be mounted thereon and connected to the clutch 24 to permit manual operation.

In operation, as the device is propelled over the surface of a lawn or in an area where leaves are on the ground, the drum 14 will be rotated at a relative high speed, and the brushes 16 will pick up the leaves and throw them into the housing. A suitable adjustable guard 27 may be mounted on the forward end of the housing 3 to assure the movement of the leaves so picked upwardly into the housing 3. The speed of rotation of the drum 14 and the extended brushes 16, will create a current of air towards the rear of the device, which will aid in carrying the leaves rearwardly on the table 17 and into the path of the rotating pulverizing drum 19. The leaves will be urged downwardly between the wire brushes of the drum 19 and the wire brushes 23 of the grate 21 and will be broken and pulverized, and the material thereof sifted through the ports 22 back onto the lawn. Twigs and sticks and other foreign matter that may pass through the area between the pulverizing drum and the grate will drop out of the housing through the area between the terminus of the guard 20 and the end of the grate 21.

While the foregoing is considered a preferred form of the invention, it is by way of illustration only, the broad principle of the invention being defined by the appended claim.

40 What we claim is:

In a leaf disposal device, a wheeled framework, a housing mounted on said framework, a source of power mounted on said housing having a driving pulley, a rotating drum mounted in said housing having a driven pulley, a belt connecting said driving and driven pulleys and means for moving said belt into and out of driving relation, a plurality of outwardly extending brushes longitudinally mounted on said drum, a rearwardly and downwardly extending table mounted in said housing, having its uppermost end immediately adjacent the extended ends of said brushes, a pulverizing drum mounted in said housing adjacent the opposing end of said table, said pulverizing drum having outwardly extended peripheral brushes, a grate mounted on said housing adjacent said pulverizing drum shaped to conform to the contour of said drum and terminating beneath said drum, said grate having a plurality of orifices therethrough and a plurality of inwardly extended brushes adapted to cooperate with the peripheral brushes on said pulverizing drum.
